UNITED STATES PATENT OFFICE

CARL THOMAS CARLSON, OF CHATTANOOGA, TENNESSEE, ASSIGNOR TO ERIE CITY IRON WORKS, OF ERIE, PENNSYLVANIA, A CORPORATION OF PENNSYLVANIA

WALL STRUCTURE

Application filed February 3, 1928. Serial No. 251,627.

This invention is designed to improve furnace walls, or walls subjected to heat. Such walls are usually provided with a lining, or refractory wall subjected directly to the intense heat of the furnace and a shell, or outer wall which protects and insulates the refractory. It is desirable to tie these walls together and the present invention is directed to a structure for accomplishing this purpose.

10 A preferred embodiment of the invention is illustrated in the accompanying drawings as follows:—

Fig. 1 shows a vertical section through the wall on the line 1—1 in Fig. 2.

15 Fig. 2 an elevation of the inner face of the wall.

Fig. 3 a perspective view of one of the cross tie bricks.

20 Fig. 4 a perspective view of a tie plate. 1 marks the inner wall. This is formed of refractory brick. Arranged in this wall are cross bricks 2 preferably of a thickness involving two courses of the ordinary brick. This cross brick projects outwardly from the 25 outer face of the inner wall and has a lip 3.

The outer wall 4 may be formed with ordinary brick. Arranged between courses of the brick is a tie plate 5 with a turned-up edge, or hook 6 at its inner end. This hook 30 engages the lip 3.

It will be noted that using the metal plate permits of a comparatively thin hook 6 giving up to the lip 3 formed on the cross brick the greater part of the available space between the walls, thus making it possible to make the lip of the cross brick of sufficient strength.

I prefer to step the courses 7 immediately below the plate 5 inwardly from the inner 40 face of the outer wall and under the plate 5 thus bracing this plate and holding it more surely in engagement with the cross bricks when subjected to the intense heat.

What I claim as new is:—

45 In a wall structure, the combination of an inner wall formed of refractory brick comprising cross brick projecting from the outer face of the inner wall, said cross brick having a projecting lip on its projecting end; an 50 outer wall of brick spaced apart from the

inner wall and having inserted in its courses a metal plate projecting from the inner face of the outer wall and having a hooked end engaging the lip of the cross brick, the brick of the immediate courses below the plate being stepped inwardly from the inner face of the inner wall under the plate. 55

In testimony whereof I have hereunto set my hand.
